KNITTING MACHINE

Frank G. Weisbecker, Glenside, Pa., assignor to
Hosiery Patents Incorporated, Lansdale, Pa., a
corporation of Pennsylvania

Application March 19, 1940, Serial No. 324,864

46 Claims. (Cl. 66—110)

This invention relates to improvements in knitting machines, and particularly to improvements in the catch bar mechanism of straight knitting machines, such as are used, for example, in the production of full-fashioned hosiery. The expression "catch bar mechanism," as used herein, is to be understood as including a catch bar and also the means which actuate the catch bar and control its operation.

The straight knitting machines now commonly used in the production of full-fashioned hosiery comprise a plurality of knitting sections for simultaneously producing a corresponding number of stocking blanks. Each of these knitting sections includes a bank of knitting needles, one or more yarn carriers for laying yarn along the needles, a series of reciprocable sinkers to be advanced in succession for sinking the laid yarn between certain of said needles, and a series of dividers which are moved en masse to complete the yarn sinking operation. The means for advancing the sinkers comprises a longitudinally reciprocable slur cock bar, which supports a number of slur cams, there being a slur cam for each knitting section of the machine. Each slur cam moves with the slur cock bar and advances, in succession, the sinkers of the corresponding knitting section. In some types of conventional straight knitting machines, the slur cams have direct engagement with the corresponding sinkers. In certain other types of straight knitting machines, each沉er is engaged directly by a沉er jack. These沉er jacks are directly engaged by the slur cam of the same knitting section and are operated in succession thereby to provide a corresponding operation of the associated sinkers.

The dividers of conventional straight knitting machines are advanced en masse immediately upon completion of the沉er advancing operation by the slur cams. This advancing movement of the dividers is provided by a catch bar. This catch bar is operated so as to have movement in both a horizontal direction and a vertical direction. The catch bar, according to conventional practice, is at all times in engagement with the dividers so that the latter are actuated by the catch bar as it travels horizontally in both its advancing and withdrawing movements. The catch bar is lowered into engagement with the re-advanced sinkers, so that the latter will be retracted as the catch bar is withdrawn to its rearward position.

In conventional straight knitting machines, the vertical movement of the catch bar is effected

5 by a so-called front or vertical catch bar motion, and the horizontal catch bar movement is provided by a so-called back or horizontal catch bar motion. The so-called front or vertical catch bar motion includes a single front catch bar shaft and a system of levers, which are operated from the main cam shaft of the knitting machine. The back or horizontal motion for the catch bar comprises a single back catch bar shaft and a system of levers which are operated from the main cam shaft of the knitting machine.

10 The cam shaft of the conventional straight knitting machine is provided with a number of cam discs, which have cam surfaces on their peripheral edges. The so-called front and back catch bar motions each include cam levers having rollers or followers which ride on the periphery of certain of these cam discs. Stout springs are provided to urge the cam levers of the back catch bar motion in a direction to maintain contact between their cam rollers and the peripheries of the corresponding cam discs on the main cam shaft. The cam levers of the front catch bar motion are urged into engagement with their cam discs by reason of the weight of the catch bar, which force may be supplemented by a conventional cam lever spring.

15 Another feature of many conventional straight knitting machines is their substantial length, due to the fact that they usually contain as many as 20 or 24 knitting sections arranged in end to end relation. It is the practice in the art to provide these multi-section straight knitting machines with a single, unitary catch bar, a single, unitary front catch bar shaft, and a single, unitary back catch bar shaft, each bar and shaft extending substantially the entire length of the knitting machine for operating the sinkers and dividers of all the knitting sections in the manner described above. The conventional catch bar is made as a single, solid bar, or from several sections which are rigidly connected to act as a unit.

20 The conventional catch bar mechanism has a number of disadvantages. It frequently happens that the catch bar does not act in proper timed relation with outer operating elements of the knitting machine. As a result, machine parts are apt to be damaged, and hosiery is apt to be imperfectly produced. For example, the catch bar is sometimes prematurely lowered into engagement with the sinkers. This may be due to some machine part getting out of adjustment. If any沉er is being held by the catch bar when the slur cam is attempting to operate it, a沉er

smash usually takes place. In a sinker smash, the sinkers are broken or damaged. If the machine has sinker jacks, they will also be broken or damaged.

A single, unitary catch bar for a straight knitting machine having a number of knitting sections presents certain objections. It is difficult, for example, to maintain the entire length of the catch bar in alignment and to have the catch bar operate the sinkers and dividers throughout the machine in substantially the same manner. If the catch bar mechanism of conventional knitting machines requires adjustment at any knitting section of the machine, it is extremely difficult to provide the adjustment without at the same time disturbing the adjustment of the catch bar mechanism at other knitting sections along the machine.

The front catch bar motion of conventional form takes up space at the front of the knitting machine, where the actual knitting takes place, and thereby crowds the machine at the places where free space is highly desirable. In conventional knitting machines, the front side thereof is generally so crowded with machine parts that the machine attendant is hampered in his work. The usual front catch bar motion also occupies space which may be advantageously used for mounting other mechanisms.

It is, therefore, one of the objects of this invention to provide an improved catch bar mechanism for straight knitting machines.

Another object of this invention is to provide improvements in a straight knitting machine catch bar mechanism, whereby premature engagement between the catch bar and the sinkers is avoided.

Still another object is to provide such a control for a catch bar of a straight knitting machine that the catch bar will be certain to act in the desired timed relationship with the other operating mechanisms of the knitting machine.

A further object is to simplify catch bar mechanisms.

Still another object is to eliminate the need for the conventional front catch bar motion. By attalning this object, the knitting machine is relieved of much weight and is provided with more free space at its front.

Still another object is to provide a novel and improved form of catch bar means, and novel means for operating and controlling the same.

Another object of this invention is to provide a knitting machine with a catch bar divided into sections, and means for so supporting and operating the catch bar sections that each may be individually adjusted and actuated according to the requirements of the corresponding sinkers and dividers.

Still another object is to provide an improved vertical catch bar motion and also an improved horizontal catch bar motion.

Other objects and advantages of this invention will be clear from the following description, the appended claims and the accompanying drawings, which illustrate a preferred embodiment.

In the accompanying drawings, Figure 1 is a transverse, vertical cross-sectional view of a straight knitting machine, and shows a catch-bar mechanism embodying this invention.

Figure 2 is an enlarged view of a detail of Figure 1.

Figure 3 is a rear elevational view of the struc-

ture of Figure 1, but with the sinkers and the sinker assemblies shown more or less diagrammatically. Figure 3 illustrates a six-section machine, that is one having six knitting sections.

Figure 4 is a top plan view of the structure in Figure 3.

Figure 5 is a view corresponding to Figure 1, and shows another embodiment of this invention. Figure 6 is a rear elevational view of a detail

of Figure 5.

Figure 7 is a transverse, vertical, sectional view through a straight knitting machine and illustrates a further embodiment of this invention.

Figure 8 is a transverse vertical section of a straight knitting machine, and illustrates an embodiment of this invention which eliminates entirely the need for the conventional type of front catch bar motion.

Figures 9 through 12 are views to illustrate a sequence of operations for the embodiment of Figure 8.

Figure 13 is a perspective view of another embodiment which eliminates the need for the conventional front catch bar motion.

Figure 14 is an enlarged view of a detail of Figure 13.

Figures 15 through 19 are views to illustrate a sequence of operations for the embodiment of Figure 14.

Figure 20 is a rear elevational view of the embodiment of Figure 13. Figure 20 illustrates six knitting sections which may be the knitting sections of a six-section machine, or a part of all the knitting sections in a larger machine such as a twenty or twenty-four section straight knitting machine.

Figure 21 is a detail view taken on line 21-21 of Figure 20.

Referring now to the drawings, conventional straight knitting machines include a number of machine frames 1, a front rail or beam 2, a rear beam or rail 3, and a main cam shaft 4. The usual practice is to space the frames 1 a distance of two knitting sections KS. It is also the usual practice to have the rails 2 and 3 and the cam shaft 4 extend the full length of the machine and be supported by the frame 1.

Each knitting section KS usually has a number of conventional yarn carriers (not shown) for laying yarn along sinkers 5 and a conventional bank of needles (not shown). Each knitting section KS also has a plurality of the sinkers 5 alternating with a series of dividers 6. The sinkers 5, after each yarn laying operation by the yarn carriers (not shown), are advanced, in succession, by means of a series of jacks 7, there being a jack 7 for each sinker 5. The jacks 7 are pivotally mounted on a rod 8, and are moved

are pivotally mounted on a rod 8, and are moved in a clock-wise direction (see Figure 3) to advance the corresponding sinkers 5. The jacks 7 of a knitting section KS are actuated in succession by a slur cam 9, there being a slur cam 9 for each knitting section KS. Each of these slur cams 9 is carried by a slur cock box 10, and all of the slur cock boxes 10 are secured to a common slur cock bar 11. The slur cock boxes 10 are mounted for reciprocating sliding movement on a stationary bar 28 according to conventional practice. The slur cock bar 11 usually extends the combined length of all the knitting sections KS and may be longitudinally reciprocated by the conventional Coulier mechanism, or any other suitable means. It will thus be understood that all of the slur cock boxes 10 and their slur

cams 9 partake of the reciprocatory movement of the slur cock bar 11 and that each slur cam 9 is effective in both directions of travel to actuate the jacks 7 and advance the sinkers 5 in succession.

At the completion of the operation for advancing the sinkers 5, the dividers 6 are moved forwardly en masse to complete the operation for sinking the yarn between the usual knitting needles (not shown). This movement of the dividers 10 5 is provided by catch bar means 12 having a longitudinally extending groove 13 in its under side (see Figure 2).

The catch bar means 12 is so operated as to have movement in both vertical and horizontal 15 directions, whereby it is effective to advance the dividers 6 and retract both the dividers 6 and the sinkers 5.

Proper operation of the catch bar means 12 calls for its being placed in an upper elevated and 20 rearward position (see Figures 1 and 2) prior to the sinker advancing operation of the slur cams 9, so that the forward edge 14 of its under side is above the heads or butts 15 of the sinkers 5, and its groove 13 retains the heads or butts 16 25 of the dividers 6. The catch bar means 12 is, therefore, in such position as not to interfere with the sinkers 5 being advanced or projected forwardly toward the front of the machine by the slur cams 9. During the sinker advancing 30 movement, the catch bar means 12 is maintained in its elevated rearward position and the dividers remain in their rearward position (see Figures 1 and 2). Following the described sinker advancing operation, the catch bar means 12, while it 35 maintains its elevated position, is advanced toward the front of the machine to advance the dividers 6 en masse. After the catch bar means 12 reaches a forward position, it is lowered to bring its front edge 16 below the tops of the 40 sinker heads or butts 15 and to place the latter within the groove 13. During this lowering operation of the catch bar means 12, both it and the sinkers 5 are in an advanced position. The catch bar means 12, while in its lowered position, is moved rearwardly to withdraw or retract both the dividers 6 and the sinkers 5. When the sinkers 5 and the dividers 6 reach their rearward 45 position, the catch bar means 12 is raised to its elevated position (see Figures 1 and 2) and thereby releases the sinkers 5 for their next operation by the slur cams 9.

According to the embodiment of Figures 1 through 4, the described operation of the catch bar means 12 is provided by the joint action of front and back catch bar motions. The back or horizontal catch bar motion comprises shifter arms 25, and levers 26 and 27 which levers are 50 adjustably, yet rigidly, secured to back catch bar shafts 28. The shifter arms 25 are pivotally secured to the levers 26 and move the catch bar means 12 toward and away from the front of the machine (at the right in Figure 1) during oscillation of the back catch bar shafts 28. A cam roller or follower 29 is carried by each of the cam levers 27 and is held against the periphery of a suitable cam 30 on the main cam shaft 4 by means of a stout spring 31' (see Figure 1). The cams 30 are knitting cams, and each cam 30 has at its side a so-called narrowing cam 31 (see Figure 3), which in known manner is moved into engagement with the adjacent cam roller 29 when the main cam shaft 4 is longitudinally shifted for the usual narrowing operation.

The front catch bar motion includes connecting pieces 35, each of which is rigidly secured at one end to the catch bar means 12 and is supported at its opposite end by means of a lifter arm 36. Levers 37 and 38 are adjustably secured to front catch bar shafts 40, and are actuated from the cam shaft 4 to operate the lifter arms 36. The levers 37 are pivotally connected to their respective lifter arms 36. The cam levers 38 are provided with rollers or followers 42 for engagement with the periphery of the knitting cams 41. Cam lever springs (not shown) are sometimes provided to maintain the followers 42 and cams 41 in engagement, although the catch bar means 12, if of heavy construction, may be sufficient to keep the roller 42 on the periphery of cam 41. A narrowing cam 39 is usually provided at the side of each front catch bar motion knitting cam 41. These narrowing cams 39 move into operative engagement with the adjacent cam followers 42 when the cam shaft 4 is shifted for the usual narrowing operation.

The catch bar means 12 of this invention is of a novel and improved form. The catch bar means 12 comprises a number of sections preferably one section for every two knitting sections KS. Figures 3 and 4 show a machine having six knitting sections KS and the catch bar means 12 in three sections numbered 45, 46 and 47 respectively. Each of these three sections 45, 46 and 47 may be considered a short catch bar for the sinkers and dividers of two knitting sections. Each of the outer two catch bar sections 45 and 47 has secured to its inner end a flat plate-like member 48. These members 48 project beyond the ends of the respective catch bar sections 45 and 47 and provide a rest or support for the ends of the intermediate catch bar section 46. The catch bar section 46 is laterally and freely slidable on the members 48, that is, it is free to slide on the members 48, so as to be independently movable at all times toward and away from the front of the knitting machines. The catch bar section 46, however, is so supported by the members 48 that it is elevated by the catch bar sections 45 and 47 when the latter are raised. As the catch bar section 46 rests by gravity action on the members 48, the section 46 may partake of the movement of the catch bar sections 45 and 47 when the latter are lowered.

According to the Figures 3 and 4 construction, each of the three catch bar sections 45, 46 and 47 is provided with a separate back or horizontal catch bar motion, but only the catch bar sections 45 and 47 are provided with a front or vertical catch bar motion, as the intermediate catch bar section 46 derives its vertical movement from the outer two catch bar sections 45 and 47.

The Figures 3 and 4 construction, therefore, includes three independent back catch bar motions and two independent front catch bar motions. Each back catch bar motion has a cam lever 27, a catch bar shaft 28, a set of two levers 26, and a set of two shifter arms 25. The shifter arms 25 of each set are preferably arranged adjacent the opposite ends of the corresponding catch bar section (45, 46 or 47). The three catch bar shafts 28 preferably have their ends journaled in bearings 50 which are carried by the frames 1. If desired, an oil soaked pad, or other lubricating means may be interposed between the adjacent ends of the shafts 28.

The two front catch bar motions of Figures 3 and 4 are entirely independent. Each of these

two front catch bar motions may include a cam lever 38, a front catch bar shaft 49, a set of two levers 37, a set of two lifter arms 36, and a set of two connecting pieces 35. The connecting pieces 35 in each set thereof are preferably secured to the corresponding catch bar section (45 or 47) adjacent the opposite ends thereof.

In the practice of this invention according to the Figures 3 and 4 construction, each catch bar section (45, 46 and 47) and its particular operating means may be separately adjusted and regulated according to the requirements of its corresponding two knitting sections KS. Should any one of the catch bar sections 45, 46 and 47 get out of adjustment or become inoperative, the other two catch bar sections may continue to function in desired manner. Either one of the end catch bar sections 45 and 47 is capable of providing the desired vertical movement for the intermediate catch bar section 46. As catch bar section 46 is laterally slideable (that is movable toward or away from the front of the knitting machine) on the plate members 48, each of the three back or horizontal catch bar motions may be individually adjusted without effecting the operations, adjustments or timing of the other two back catch bar motions and their respective catch bar sections.

If this invention is applied to a knitting machine having more than six knitting sections KS, it will be obvious how the invention may be applied thereto. For example, a twenty-two section machine may be provided with eleven catch bar sections, a corresponding number of independent back or horizontal back catch bar motions, and a separate front or vertical catch bar motion for each of the odd-numbered catch bar sections. The even-numbered catch bar sections may be supported, raised and lowered in the manner illustrated and described for the catch bar section 45 of Figures 3 and 4.

This invention also provides means for so controlling the catch bar means 12 that the same may not be accidentally lowered while the slur cams 9 are performing the sinker advancing operations. This catch bar control includes one or more control members or elements 60. With a knitting machine as shown in Figures 3 and 4, there may be three of the control members 60, one for each of the three catch bar sections 45, 46 and 47. If desired, the control member 60 for the central catch bar section 46 may be omitted, and the latter may depend on the other catch bar sections 45 and 47 for being maintained in the elevated position during sinker advancing operations. The control members 60 are preferably arranged in close proximity to the catch bar means 12 and may be actuated by suitable means which is conveniently located. The operating means for each member 60 may be a reciprocating means having a path of movement paralleling that of the slur cams 9. A particularly suitable operating means for the control members 60 is the reciprocable slur cock bar 11. Each control member 60 may, therefore, be carried by a set of brackets 61 which are suitably secured to the slur cock bar 11, as for example, to the under side thereof (see Figures 1 to 3).

Each control member 60 may have the form of a bar, as shown in the figures, with a flat top side surface 59 and sloping ends 63 and 64 (see Figures 3 and 4). For each control member 60, there is a corresponding roller or fol-

lower member 62 which is carried by the respec-

tive catch bar section of the catch bar means 12. Each control member 60 is so carried and supported by the slur cock bar 11 that its flat top side 59 passes under and then beyond the corresponding roller 62 in each complete stroke of the slur cock bar 11. The relationship of each control member 60 and its roller 62 is such that the top surface 59 of the control member 60 is below the roller 62 during the entire time that the sinkers 5 are being advanced by the slur cams 9. The surface 59 may be at such elevation as to actually provide support for the corresponding roller 62 and its catch bar section during the sinker advancing operation, or the surface 59 may be at a slightly lower level, so that it has actual engagement with the roller 62 only in the event that the vertical catch bar motion fails to properly support the catch bar section in question. In either case, the top surface 59 is positioned to act as a barrier to such lowering movement of the respective roller 62 as would permit the respective catch bar section to place its edge 14 in front of the sinker butts 15 before the sinkers 5 are advanced.

As all the control elements 60 are similarly constructed and have similar operations, a description for one of the control elements 60 will suffice for all of them. When the yarn carriers (not shown) are laying thread, the catch bar means 12 is in its rearward and elevated position (see Figures 1, 2 and 3) and the slur cock bar 11 is in position to start a stroke, for example, toward the left (see Figures 3 and 4). At this time, each slur cam 9 and its slur cock box 10 is arranged somewhat beyond the end of the bank of sinkers 5 and dividers 6 of the corresponding knitting section KS. Each of the control members 60 is also now in such position that its top side 59 is beyond and somewhat to the right of the corresponding roller 62 (see Figures 3 and 4). When the slur cock bar 11 begins its travel to the left (looking at Figures 3 and 4), each control member 60 has its leading end 63 pass under and beyond the respective roller 62 before the corresponding slur cam 9 engages any of the sinkers 5. In the event a catch bar section is not in the raised position when the slur cams 9 are approaching the sinkers 5 to begin the sinker advancing operation, the leading end 63 of the corresponding control member 60 acts as a cam face on the respective roller 62 and elevates the catch bar section to free the sinkers 5 for actuation by the slur cams 9. The surface 59 of each control member 60 is of such length as to continue to provide support for the respective roller 62 and the corresponding catch bar section (see Figures 1 and 2) until the slur cams 9 have projected all the sinkers 5. It may be noted at this point that Figures 1 and 2 show the slur cam 9 in the process of advancing the sinkers 5, and a control member 60 in position to preclude lowering of the associated catch bar. As the slur cams 9, their slur cock boxes 10, and the slur cock bar 11 approach the limit of their travel toward the left (looking at Figures 3 and 4), after the completion of the sinker advancing operation, the control members 60 reach a position in which they free the rollers 62. The back catch bar motions now operate to advance the catch bar means 12 and the dividers 6 toward the front of the machine. The front catch bar motions operate to lower the catch bar means 12 into engagement with the sinkers 5, after which the catch bar means 12 is retracted and then elevated to the position shown

in Figures 1, 2 and 3. The slur cock bar 11 now reverses its direction and travels to the right (looking at Figures 3 and 4). As the slur cock bar 11 travels to the right, the slur cams 9, and the control members 60 travel therewith in the same direction and function in substantially the same manner as when moving in the opposite direction. It will also be understood that the cam faces 63 and 64 of a particular cam-like or control member 60 alternate as the leading 10 cam face thereof during reciprocatory movement of the slur cock bar 11.

Each connecting piece 35 is apertured at 35' to receive the reduced end portion or stud 36' at the top of the corresponding lifter arm 36 (see Figures 1 and 3). This stud 36' and aperture 35' connection provides an operative relation between each arm 36 and the associated connecting piece 35 during normal operation of the front catch bar motions. Should one of the latter motions get out of adjustment or become defective, the stud and aperture connections permit the necessary vertical movement of the connecting pieces 35 relative to their lifting arms 36 when a control member 60 cooperates with its roller 62 to raise the corresponding catch bar section and the connecting pieces 35 secured thereto. During this relative vertical movement, the pieces 35 rise to only a slight degree and do not slip off the ends of the studs 36'. Under normal operating conditions, the weight of each catch bar section is sufficient to cause its connecting pieces 35 to rest on the upper ends of the lifting arms 36 so that each catch bar section will partake of the vertical movements of its lifting arms 36.

Figures 5 and 6

The machine shown in Figures 5 and 6 is substantially the same as that shown in Figures 1 through 4 except that Figures 5 and 6 show the catch bar control means arranged between the slur cock bar 11 and the front catch bar shaft 40. In Figures 5 and 6, the front catch bar shaft 40 carries a third lever arm 65. This lever arm 65 and the cam lever 67 may be of integral construction, or the lever arm 65 may be separately formed and, adjustably, yet rigidly, secured to the shaft 40. The lever arm 65 is connected by a link 66 to the lower end of a two-arm lever 67. This two-arm lever 67 is pivotally mounted on a shaft 68 which is suitably supported by the machine frame.

The cam lever 67 and the front catch bar shaft 40 are so connected by the link 66 and the arm or lever 65 that movement of one causes movement of the other in reverse direction. For example, anti-clockwise movement of the cam lever 67 produces clockwise movement of the shaft 40 (Figure 5) to elevate the catch bar means 12. When the cam 41 produces clockwise rotation of the shaft 40 for raising the catch bar means 12, the cam lever 67 is simultaneously moved anti-clockwise.

A cam-like control member 70 is suitably and rigidly secured to the slur cock bar 11 so as to reciprocate or travel therewith. During the reciprocatory movement of the slur cock bar 11, the control member 70 cooperates with a roller or cam follower 69 which is carried by the lever 67. The cam-like control member 70 has the same general function and construction as the control members 60 of Figures 1 through 4. For example, the control member 70 may have a flat side face 71 and cam faces 72 and 73 at the 75

opposite ends thereof corresponding to the faces 59, 63 and 64 respectively of the Figures 1 to 3 control members 60.

When the slur cock bar 11 begins a stroke and the slur cams 9 are about to begin a sinker advancing operation, the catch bar means 12 should be in the elevated position thereof. If the catch bar means 12 is not in its upper position at this time, the cam roller 69 will be in the path of the leading cam face (for example 72) of the control member 70. The roller 69 will then, in effect, roll or travel up the leading cam face (72 for example) during movement of the slur cock bar 11 and cause the lever 67 to rock anti-clockwise (looking at Figure 5) before any sinker 5 is engaged by its slur cam 9. This rocking movement of the cam lever 67 results in the catch bar means 12 being simultaneously elevated to free the sinkers 5 for actuation by the corresponding slur cams 9. The side 71 of control member 70 is of such character and length as to cooperate with the roller 69 to preclude lowering of the catch bar means 12 into engagement with the sinkers 5, as long as the slur cams 9 are actually engaged in advancing the sinkers 5. When the side 71 is opposite the roller 69, the cam lever 67 cannot be rotated clockwise (looking at Figure 5) and the front catch bar shaft 40 is prevented from having such motion as will permit lowering of the catch bar means 12 into engagement with the sinkers 5.

The side surface 71 of the control member 70 is also of such length that it passes beyond the roller 69 after completion of the sinker advancing operation by the slur cams 9 and while the slur cock bar 11 is approaching the limit of its travel.

The back and front catch bar motions now proceed to function in such manner as to advance, lower, and retract the catch bar means 12 to secure the usual operations for the dividers 6 and the sinkers 5.

On the return stroke of the slur cock bar 11, the control member 70 travels therewith and performs the same functions as those just described for its operation in its other direction of movement.

In a knitting machine having a single front catch bar shaft, it may be desirable to have but a single control between such shaft and the slur cock bar 11. In a six-section machine having a three section catch bar means 12 as in Figures 3 and 4, it would be desirable to have a separate control for each of the shafts 40.

Figure 7

The construction of Figure 7 has the same sinker advancing mechanism and the same back catch bar motion as Figures 1 through 6. In Figure 7, however, a different arrangement is provided for the front catch bar motion and also for the catch bar control. The front catch bar shaft 40, in the Figure 7 construction, is in a position substantially closer to the back catch bar shaft 28 to provide more free space at the front of the machine. The lever arms 37 and 38 of the front catch bar motion, in the Figure 7 construction, are so arranged on the catch bar shaft 40 that the cam 41 moves the cam lever arm 38, the catch bar shaft 40, and the lever arms 37 anti-clockwise to raise the lifter arms or members 36 and the catch bar means 12 supported thereby. When the cam 41 allows clockwise movement of the cam lever 38, the catch bar means 12 may descend to its lower position by gravity action.

The catch bar control of the Figure 7 construction comprises a cam-like member 80, a cam follower or roller 82, and a cam lever 83. The cam-like member 80 may, for example, have the same construction as the cam-like member 70 of Figures 5 and 6, and may be carried by brackets 81 extending from the under side of the slur cock bar 11. The cam-like member 80 is so supported from the slur cock bar 11 as to coact with the cam roller or follower 82 in the same manner as explained above with regard to the control member 70 and the roller 69 of Figures 4 and 5.

In the Figure 7 construction, the cam lever 83 is rigidly, yet adjustably, secured to the front catch bar shaft 40, so that they have the same oscillatory or rotary movement.

The cam-like member 80, like the control member 70, is adapted to actuate its cooperating lever 83 for turning the shaft 40 and raising the catch bar means 12 if the latter is not elevated when the slur cams 9 are about to advance the sinkers 5. The cam-like member 80, like the control member 70, serves as a barrier to clockwise movement of its cooperating lever 83 and prevents lowering of the catch bar means 12, as long as the sinkers are being advanced by the slur cams. When the sinker advancing operation is over, the cam-like member 80, like the control member 70, arrives at a position to free the lever 83 so that the catch bar means 12 may be lowered during subsequent movement of the cam 41.

Figures 8 through 12

The construction of Figures 8 through 12 includes the back catch bar motion 25 through 30, but not the front catch bar motion 35 through 42, of the constructions in Figures 1 through 7. In the construction of Figures 8 through 12, a cam-like member 88 and a roller or cam follower 81 are effective to raise the catch bar means 12 and thereby release the sinkers 5 when the slur cam 9 is about to begin the previously described sinker advancing operation. The roller 81 is supported by the catch bar means 12 in substantially the same manner as the roller 62 of Figures 1, 2, 3 and 4. The cam-like member 88 is also supported from the slur cock bar 11 by means of brackets 82 in substantially the same manner as the cam-like members 60 are supported in Figures 1 to 4. The roller 81 and the cam 88 also cooperate in substantially the same manner as described with respect to the cam-like members 60 and the rollers 62 of Figures 1 through 4.

One or more latch members 93 are provided to releasably support the catch bar means 12 in the construction of Figures 8 through 12. Each latch member 93 is pivotally secured at its lower end to a stationary part of the machine, such as an extension 94 of the sinker supporting base 95. Each latch member 93 is yieldingly urged against a suitably supported stationary pin 96 by means of a coil spring 97. The spring 97 is suitably anchored at one end to a stationary part of the machine and is effective to normally hold the latch member 93 in the upright position illustrated in Figures 8, 9 and 12. Each latch member 93 may have a roller 98 for engaging the bottom surface of the catch bar means 12 so that the latter may be readily advanced and retracted by the back or horizontal catch bar motion. A groove 99 is so formed in the lower, rear edge of the catch bar means 12 as to be in alignment with the roller 98 as the catch bar means 12 is being shifted by the back catch bar motion.

When the slur cam 9 is traveling and in the

process of advancing the sinkers 5, the relative arrangement of the machine parts is as illustrated in Figures 8 and 9. The catch bar means 12 is now in its rearward elevated position and supported by the latch member 93 as well as by the cam-like member 80.

When the slur cam 9 and the slur cock bar 11 approach the limit of their travel and all the sinkers 5 have been advanced, the cam-like member 80 is positioned similarly to the cam-like members 60 in Figure 3 and does not provide support for the catch bar means 12. The latch members 93, however, are still in the position illustrated by Figure 9 and support the catch bar means in the elevated position thereof.

The catch bar means 12 may now be shifted forwardly by the back catch bar motion to advance the dividers 6. As the catch bar means 12 moves forwardly, it brings its groove 99 into position for receiving the roller 98 of the latch member 93 (see Figure 10). The groove 99 is shaped as a cam so as to cooperate with the roller 98 and tilt the latch means 93 as the catch bar groove 13 reaches a position over the heads of the sinkers 5. Due to the roller 98 passing into the groove 99 and the tilting of the latch member 93, the catch bar means 12 is free to drop under gravity action as its groove 13 reaches a position over the heads of the sinkers 5. The illustrated mechanism now assumes the arrangement shown in Figure 10, the latch means 93 being tilted, and the catch bar means 12 being in its advanced, lower position and in engagement with the sinkers 5. The cam-like member 80 is now at one side of the roller 81. (A similar arrangement for the cam-like members 60 and the rollers 62 is shown in Figures 3 and 4.) The roller 81, however, is also at a level somewhat lower than the top surface of the cam-like member 88 as shown by Figure 10.

The catch bar means 12 is now shifted rearwardly by the back catch bar motion (25 through 30), during which shifting movement the latch member 93 is further tilted (see Figure 11).

With the relative arrangement as shown in Figure 11, the catch bar means 12 is in its rearward, lowered position, and the roller 81 is in its lowered position and in the path of travel of the cam-like member 88. The slur cock bar is now operated in a direction opposite to that of its last previous stroke or movement. Before any sinker 5 is operated by a slur cam 9, the leading end or cam face of the cam-like member 88 engages the roller 81 and raises the catch bar means 12 to its elevated rearward position (see Figure 12). During the time the catch bar means 12 is being elevated by its roller 81 and the cam-like member 88, the spring 97 draws the latch member 93 into the position of Figure 12 for supporting the catch bar means 12.

There may be as many latch members 93, cam-like members 88, and rollers 81 as may be desired. For example, if the catch bar means 12 is in sections as shown in Figures 3 and 4, there may be a corresponding number of cam-like members and followers therefor as also shown in Figures 3 and 4. Where the catch bar means 12 is of a construction as illustrated in Figures 3 and 4, it would be preferable to provide a latch member 93 adjacent each end of each catch bar section, so that there will be a set of two latch members 93 for each catch bar section. In some cases, it may be desirable to provide one latch member 93 for each catch bar section and ar-

range it below the center of its section and between two adjacent knitting sections KS.

The cam-like control members and their followers may have such relative width as desired. For example, a control member may be relatively wider than its cam follower as shown in Figures 1, 2 and 4, where the control member 60 is wider than its follower 62. Or the cam follower may be wider than its control member as shown in Figures 8 through 12 where the roller 81 is wider than its control member 90. The proportions of the cam follower and its control member are preferably such that they will cooperate in the intended manner during reciprocation of the slur cock bar 11 regardless of whether the catch bar means 12 is in its forward or rearward position during sinker advancing operations.

It will also be understood that the control member 90 of Figures 8 through 12 may have the same shape, size and construction as the control members 60 of Figures 1 through 4.

Figures 13 through 20

In the catch bar mechanism of Figures 13 and 20, the catch bar means is illustrated as being composed of a plurality of separate catch bars or catch bar sections 110, 111 and 112, each having independent movement and independent operating means. These catch bar sections 110, 111 and 112, under normal conditions, will be simultaneously operated, and each section will have the functions of conventional catch bar means. Since the catch bar sections 110, 111 and 112 are entirely independent, each may be individually adjusted to suit the requirements of the respective sinkers and dividers, and the faulty operation of one catch bar section will affect only the corresponding knitting sections KS of the knitting machine. Should any catch bar section get out of adjustment, the difficulty may be corrected while the production of hosiery blanks continues on the knitting sections provided with the other catch bar sections. Should a particular knitting section, by reason of some accident, become faulty in operation, its particular catch bar section can be swung to an inoperative out-of-the-way position, and the usual knitting operations can proceed normally at other knitting sections of the same machine.

While Figure 20 shows but three catch bar sections 110, 111, and 112 and six knitting sections KS, the invention embodied in Figure 20 may be provided in a knitting machine having more or less knitting sections and more or less catch bar sections. Preferably the machine has a catch bar section for each set of two knitting sections as shown in Figure 20. As an illustration, if the knitting machine has twenty knitting sections, there may be ten catch bar sections, each corresponding to one of the catch bar sections 110, 111, and 112 shown in Figure 20. In a twenty knitting-section machine having ten catch bar sections, each may be controlled and operated by the means about to be described for each of the catch bar sections 110, 111 and 112.

Each of the catch bar sections 110, 111 and 112 has an individual back or horizontal catch bar motion similar to the back catch bar motions shown in Figures 1 through 4. Each back catch bar motion in the Figures 13 and 20 constructions, as in the Figures 1 through 4 constructions, may comprise a set of two shifter arms 25, a set of two levers 26, a separate catch bar shaft 28, a cam lever 27 with a cam roller 29, and two

suitably shaped cams 30 and 31 mounted on the main cam shaft 4.

Each of the catch bar sections (110, 111 and 112) in the Figures 13 through 20 construction is provided with a control device CD. As the several control devices CD are of similar construction, a description of the construction and operation of one control device CD will serve for all of them.

An individual control device CD includes a cam-like means 115, which may be carried by the slur cock bar 11, and a cam roller or follower 116, which may be carried by the corresponding catch bar section (110, 111 or 112).

The cam-like means 115 comprises a divided angle bar or two parts 117 and 118 having tongues 119 and 120, which provide an overlapping joint. The cam parts 117 and 118 are slidably mounted on a supporting bar 121 and are relatively adjustable on the bar 121 to vary the overall length of the cam-like means 115. Each of the two cam parts 117 and 118 has one or more longitudinal slots in its depending leg or flange. Set screws or bolts 122 extend through these slots for securing the cam parts 117 and 118 to the bar 121 in the desired position of adjustment.

The opposite ends of the cam-like means 115, that is the outer ends of the cam parts 117 and 118, are similarly shaped, and have a stepped construction to provide two cam faces. For convenience, the cam faces of cam part 117 are referred to as cam faces L125 and L126, and the cam faces of the cam part 118 are referred to as cam faces R125 and R126.

The cam faces R125 and L125 may be similarly shaped, and due to the stepped construction are arranged closer together than the R126 and L126 cam faces. The cam faces R125 and L125 are also formed on the side of the cam-like means 115 nearer the adjacent catch bar section (111 in Figure 13) for reason which appears more fully hereinafter.

The bar 121 may be secured to the slur cock bar 11 in any suitable manner. For example, the bar 121 may be securely mounted on blocks 130 which are rigidly attached to the usual slur cock boxes 10 (as shown more clearly in Figure 13). As already explained, the slur cock boxes 10 are slidably mounted on a supporting bar 20 and secured to the slur cock bar 11 to travel therewith. The cam-like means 115, therefore, reciprocates with the slur cock bar 11, and both will always have the same rate and extent of movement. This feature is highly desirable for providing the proper timed relation of operations for the sinkers 5 and dividers 6 by the slur cams 9 and the catch bar sections (110, 111 and 112).

The roller 116 is mounted on a stud which is eccentrically secured to a disc 135. This disc 135 is carried by a pin 136 which fits within a recess of the corresponding catch bar section (see section 111 in Figure 14) and which is adjustably secured in place by a set screw 137. By loosening the set screw 137 and turning the disc 135, the roller 116 may be raised or lowered relatively to its catch bar section so as to have proper coaction with the cam-like means 115.

The relation and adjustment of a roller 116, its cam-like means 115, and the corresponding back or horizontal catch bar motion are preferably such that they operate the associated catch bar section in the manner about to be described.

Since all the catch bar sections function similarly, but independently, reference will be made to

only the operation of one catch bar section, namely 111.

Assuming the slur cock bar 11 is traveling to the left (looking at Figure 20 for example) and the slur cams 9 are in the process of advancing the sinkers 5, the cam-like means 115 provides a rest for the corresponding roller 116 (see Figure 15) and thereby supports the associated catch bar section 111 is an elevated position. During the entire sinker advancing operation, the cam-like means 115 travels relatively to the roller 116, but is positioned below the same to prevent lowering of the catch bar section 111 from its elevated position. The catch bar section 111 is now in its rearward elevated position so as to engage the dividers 6 and free the sinkers 5 according to conventional practice. During the sinker advancing operation, the roller or cam follower 116, in effect, rolls on the top of cam-like means 115, which because of its overlapping joint provides, between its ends, continuous and uniform support for the roller 116.

When the sinker advancing operation is completed, the back catch bar motion advances the catch bar section 11 to advance the dividers 6. During this shifting movement of the catch bar section 111, the roller 116 is moved toward the front edge of the cam part 118 (see Figures 15 and 16), but still remains on the top, flat side thereof so as to continue to support the catch bar section in the elevated position.

In the subsequent movement of the cam part 118 as the slur cock bar 11 is completing its leftward stroke, the roller 116 rolls down the cam face R125 (see Figures 16 and 17) and the catch bar section 111 is lowered by gravity action so that its sinker groove 13 (see Figure 14) engages the upstanding butts of the sinkers. The relation of the sinkers, the dividers and the catch bar section 111 at this time is illustrated by the corresponding parts in Figure 10.

While the catch bar section 111 is in this lowered position, it is shifted rearwardly by its back catch bar motion to retract both the sinkers and the dividers. As the catch bar section 111 is shifted rearwardly, its roller 116 moves therewith and from the position illustrated in Figure 17 to that illustrated in Figure 18.

At about this time, the slur cock bar 11 reverses its direction of movement and travels to the right (looking at Figure 20 for example). The roller 116 is now in the path of the cam face R126. During subsequent travel of the slur cock bar 11 and the cam-like means 115, and before the slur cams 9 engage any of the sinkers, the roller 116 rolls up the cam face R126 to elevate the catch bar section 111 and thereby free the sinkers. The relationship of the sinkers, the dividers and the catch bar section 111 at this time is illustrated by the corresponding parts in Figure 12.

The relative arrangement of the cam faces R125 and R126 provides for lowering of the catch bar section 111 at the desired time, and also for raising the catch bar section 111 as soon as the slur cock bar 11 begins its rightward stroke and before any sinker has been operated by a slur cam 9.

As the slur cock bar 11 continues its travel toward the right, the roller 116 is supported by cam-like means 115. The overlapping joint between the cam parts 117 and 118 avoids jumping of the roller 116 during the time it is being supported.

As the slur cock bar 11 completes its rightward

stroke and reverses its direction of movement, the roller 116 cooperates with the cam faces L125 and L126 in the same manner as described with respect to Figures 15 through 19. The roller 116 will be shifted toward the front of the machine, will roll down the cam face L125, will be shifted toward the rear of the machine, and will roll up the cam face L126. In other words, the catch bar section 111 is given the same operation in both directions of travel of the reciprocating slur cock bar 11.

The control device CD may be used to advantage on a straight knitting machine having a single, unitary catch bar for all the knitting sections in the machine. Such a machine may be provided with one or more of the control devices CD to provide the vertical motion of the catch bar and replace the usual front catch bar motion.

Each of the catch bar sections 110, 111, and 112 in its lowered position, may rest on a suitable support so that the divider heads or butts 16 are not subjected to the weight of their catch bar section. This support may be a block 140 as shown in Figure 21. This block 140 may be secured to a stationary machine part 141 conveniently located, for example, adjacent the center of the corresponding catch bar section, that is, between the two adjacent knitting sections with which the catch bar section is associated. Each block 140 provides a support on which its catch bar section slides while the latter is shifting the sinkers from their advanced position to their rearward position. It will also be understood that each block 140 prevents the divider butts 16 from engaging the top side of the groove 13 in the corresponding catch bar section (see Figure 21).

The lowered forward position of the catch bar section 111 is illustrated in solid lines in Figure 21, and its rearward elevated position is illustrated in dotted lines of the same figure.

Supports similar to the blocks 140 may be provided, if desired, for any of the catch bars or catch bar sections of the accompanying drawings.

It will be understood that the foregoing is illustrative and that the present invention includes all embodiments and modifications coming within the scope of the appended claims.

I claim:

1. In a straight knitting machine having sinkers, means for advancing said sinkers, and means adapted to releasably engage said sinkers for withdrawing the same from the advanced position thereof, the improvement comprising means interposed between said sinker advancing means and said sinker withdrawing means for maintaining said withdrawing means in sinker releasing position for at least the duration of the operation in which said sinkers are being advanced by said sinker advancing means.

2. In a straight knitting machine having reciprocal sinkers, means for advancing the sinkers in yarn sinking operations, and means for withdrawing said sinkers, said withdrawing means being movable to effect withdrawal of advanced sinkers and being further movable into a position to release said sinkers for subsequent operation by said sinker advancing means, the improvement comprising cooperative means associated with said sinker advancing means and said sinker withdrawing means respectively for maintaining said withdrawing means in sinker releasing position for at least the duration of

the operation in which said sinkers are being advanced by said sinker advancing means.

3. In a straight knitting machine having sinkers, a reciprocable slur cock bar adapted to advance said sinkers in yarn sinking operations, and movable catch bar means to releasably engage said sinkers and withdraw the same from the advanced position thereof, the improvement comprising means interposed between said slur cock bar and said catch bar means for maintaining said catch bar means in sinker releasing position for at least the duration of the operation in which said sinkers are being advanced by said slur cock bar.

4. In a straight knitting machine having sinkers, a reciprocable slur cock bar adapted in each stroke thereof to advance said sinkers in yarn sinking operations, and movable catch bar means to releasably engage said sinkers and withdraw the same from the advanced position thereof, the improvement comprising a member associated with said slur cock bar and movable therewith, and a member associated with said catch bar means for controlling the same, one of said members having a cam-like construction and being adapted during reciprocation of said slur cock bar to coat with the other member, said members in each stroke of said slur cock bar being effective to shift said catch bar means into position to release said sinkers from said catch bar means, to maintain said catch bar means in sinker releasing position during the advance of said sinkers and to release said catch bar means from said sinker releasing position after the sinkers reach the advanced position thereof.

5. In a straight knitting machine having sinkers, a reciprocable slur cock bar adapted to advance said sinkers in yarn sinking operations, and movable catch bar means to releasably engage said sinkers and withdraw the same from the advanced position thereof, the improvement comprising a member associated with said slur cock bar and movable therewith, and a member associated with said catch bar means for movement therewith, said members being adapted to coat for maintaining said catch bar means in sinker releasing position for at least the duration of the operation in which said sinkers are being advanced by said slur cock bar.

6. In a straight knitting machine having sinkers, means for advancing the sinkers in yarn sinking operations, means adapted to be lowered into engagement with the sinkers and effective in the lowered position to withdraw said sinkers from the advanced position thereof, said withdrawing means being adapted to be raised from said lowered position to release said sinkers for advancing movement by said advancing means, the improvement comprising members associated and movable with said sinker advancing means and said sinker withdrawing means respectively to control said sinker withdrawing means, said members having such relative arrangement that, at least for the duration of the operation in which the sinkers are being actuated by said sinker advancing means, said member associated with said sinker advancing means provides a barrier in the path of movement of the other member and thereby prevents lowering of the sinker withdrawing means from sinker releasing position.

7. In a straight knitting machine having sinkers, means for advancing the sinkers in yarn sinking operations, means adapted to be lowered into engagement with the sinkers and effective in the lowered position to withdraw said sinkers

from the advanced position thereof, said withdrawing means being adapted to be raised from said lowered position to release said sinkers for advancing movement by said advancing means, the improvement comprising a cam-like member, and a member adapted for engagement therewith, one of said members being mounted for movement with said sinker withdrawing means and the other member having predetermined movement, said members being adapted to cooperate and provide support for said sinker withdrawing means in raised sinker releasing position for at least the duration of the operation in which said sinkers are being advanced by said sinker advancing means.

8. In a straight knitting machine having sinkers adapted to be advanced for sinking yarn between knitting needles, and movable means engageable with said sinkers for withdrawing the same from the advanced position thereof, the improvement comprising an element longitudinally reciprocable along a path normal to the movement of said sinker withdrawing means, a cam-like member, and a member for operative engagement with said cam-like member, one of said members being associated and movable with said sinker withdrawing means and the other of said members being adapted to travel with said reciprocable element, said members cooperating during movement of said reciprocable element to maintain disengagement between said sinker withdrawing means and said sinkers for at least the duration of the operation in which said sinkers are being advanced by said sinker advancing means.

9. In a straight knitting machine having sinkers, sinker advancing means, sinker withdrawing means, a cam shaft, means operated from said cam shaft to provide for lowering of said withdrawing means to effect driving engagement thereof with said sinkers, and for raising of said withdrawing means to release said sinkers for operation by said sinker advancing means, the improvement comprising control members carried by said sinker advancing means and said sinker withdrawing means respectively, said control members being adapted to cooperate for maintaining said sinker withdrawing means in raised sinker releasing position for at least the duration of the operation in which said sinkers are being advanced by said sinker advancing means.

10. In a straight knitting machine having sinkers, a reciprocable slur cock bar adapted during part of each stroke to advance said sinkers in yarn sinking operations, and movable catch bar means to releasably engage said sinkers and withdraw the same from the advanced position thereof, the improvement comprising a roller mounted on said catch bar means, and cam-like means supported to travel with said slur cock bar and adapted to engage said roller to thereby support said catch bar means in a raised sinker releasing position during that part of each stroke of the slur cock bar in which the slur cock bar is effective to advance said sinkers.

11. In a straight knitting machine having sinkers, sinker advancing means, sinker withdrawing means, a cam shaft, means operated from said cam shaft to provide for lowering of said withdrawing means to effect driving engagement with said sinkers, and for raising of said withdrawing means to release said sinkers for operation by said sinker advancing means, the improvement comprising control members carried by said sink-

er advancing means and said sinker withdrawing means respectively, said control members being adapted to cooperate for positioning said sinker withdrawing means in raised sinker releasing position in advance of each operation of the sinkers by said sinker advancing means.

12. In a straight knitting machine having sinkers, reciprocable sinker advancing means, sinker withdrawing means, a cam shaft, means operated from said cam shaft to provide for lowering of said withdrawing means to effect driving engagement with said sinkers, and for raising of said withdrawing means to release said sinkers for operation by said sinker advancing means, the improvement comprising control members carried by said sinker advancing means and said sinker withdrawing means respectively, said control members being adapted to cooperate for positioning said sinker withdrawing means in raised sinker releasing position in advance of each operation of the sinkers by said sinker advancing means, for maintaining said sinker withdrawing means in sinker releasing position for the duration of the operation in which said sinkers are being advanced by said sinker advancing means, and for releasing said sinker withdrawing means after the conclusion of each sinker advancing operation.

13. In a straight knitting machine having sinkers, means for advancing said sinkers, and means adapted to releasably engage said sinkers for withdrawing the same from the advanced position thereof, the improvement comprising a cam-like member supported by and movable with said sinker advancing means, and a roller supported by the sinker withdrawing means and adapted to ride on said cam-like member during sinker advancing operations for maintaining said sinker withdrawing means in sinker releasing position.

14. In a straight knitting machine having sinkers, a slur cock bar longitudinally reciprocable for advancing the sinkers, and a catch bar having horizontal motion for withdrawing the advanced sinkers and also vertical movement for engaging and releasing the sinkers, the improvement which comprises two members associated and movable with said slur cock bar and said catch bar respectively, said members being so relatively arranged as to be adapted to have engagement with each other for maintaining the catch bar in its elevated position at least for the duration of the operation in which said sinkers are being advanced by said sinker advancing means.

15. In a straight knitting machine, the combination comprising a catch bar adapted to have reciprocating movement in both vertical and lateral directions, a reciprocable slur cock bar, a cam-like member, and a member for cooperating with said cam-like member, one of said members being supported by said slur cock bar and reciprocable therewith, and the other of said members being supported by and movable with said catch bar, said members in each stroke of said slur cock bar being adapted to have interengagement for raising said catch bar and maintaining the catch bar in the elevated position for a predetermined part of the stroke and then releasing said catch bar for lowering movement.

16. In a straight knitting machine, the combination comprising a catch bar adapted to have reciprocating movement in both vertical and lateral directions, a reciprocable slur cock bar, a member supported by said slur cock bar and re-

ciprocable therewith, and an element supported by and movable with said catch bar, said member in each stroke of said slur cock bar being adapted to pass under said element while said catch bar is in an elevated position and thereby maintain said catch bar in the elevated position until said member has passed beyond said element.

17. In a straight knitting machine, the combination comprising catch bar means, a cam shaft, means operated by said cam shaft for imparting horizontal movement to said catch bar means, and means adjacent said catch bar means and including a cam-like element and an element for engaging said cam-like element, one of said elements being associated with said catch bar means to move therewith, the other of said elements having movement relative to said catch bar element for actuating the same to raise and lower said catch bar means.

18. In a straight knitting machine, the combination comprising vertically movable catch bar means, a reciprocable slur cock bar, a cam roller supported by said catch bar means, and a cam-like element supported by and movable with said slur cock bar, said cam-like element being adapted to cooperate with said roller for raising and lowering said catch bar means in each stroke of said slur cock bar.

19. In a straight knitting machine having sinkers, sinker advancing means, catch bar means to withdraw advanced sinkers and being adapted to be raised and lowered for releasing and engaging said sinkers, an oscillatable catch bar shaft, means interposed between said catch bar shaft and said catch bar means to raise and lower said catch bar means during oscillation of said shaft, and cooperating means associated with said sinker advancing means and said catch bar shaft respectively to control said shaft for maintaining said catch bar means in raised sinker releasing position at least for the duration of the operation in which said sinkers are being advanced by said slur cock bar.

20. In a straight knitting machine having sinkers, the combination comprising a reciprocable slur cock bar adapted during each stroke thereof to advance said sinkers, catch bar means for withdrawing said sinkers, a cam shaft, a catch bar shaft, a plurality of arms rigidly secured to said catch bar shaft, one of said arms being actuated by said cam shaft for oscillating said catch bar shaft, operating means interposed between another one of said arms and said catch bar means to raise and lower the latter for releasing and engaging said sinkers as said catch bar shaft is oscillated, and control means interposed between a third one of said arms and said slur cock bar to control said catch bar shaft for maintaining said catch bar means in raised sinker releasing position at least for the duration of the operation in which said sinkers are being advanced by said slur cock bar in each stroke thereof.

21. In a straight knitting machine having sinkers, the combination comprising sinker advancing means, catch bar means to withdraw advanced sinkers and being adapted to be raised and lowered for releasing and engaging said sinkers, an oscillatable catch bar shaft, means interposed between said catch bar shaft and said catch bar means to raise and lower said catch bar means during oscillation of said shaft, and cooperating means associated with said sinker advancing means and said catch bar shaft re-

spectively to control said shaft for maintaining said catch bar means in raised sinker releasing position at least for the duration of the operation in which said sinkers are being advanced by said slur cock bar, said cooperating means including a cam-like member associated with said sinker advancing means for movement therewith and a follower member operatively connected to said catch bar shaft and adapted to coact with said cam-like member.

22. In a straight knitting machine having sinkers, the combination comprising a reciprocable slur cock bar adapted during each stroke thereof to advance said sinkers, catch bar means for withdrawing said sinkers, a cam shaft, a catch bar shaft, a plurality of arms rigidly secured to said catch bar shaft, one of said arms being actuated by said cam shaft for oscillating said catch bar shaft, operating means interposed between another one of said arms and said catch bar means to raise and lower the latter for releasing and engaging said sinkers as said catch bar shaft is oscillated, a cam-like member mounted to travel with said slur cock bar, and a follower member carried by a third one of said arms, said members during each stroke of said slur cock bar being adapted to control said catch bar shaft for maintaining said catch bar means in raised sinker releasing position at least for the duration of the operation in which said sinkers are being advanced by said slur cock bar.

23. In a straight knitting machine, the combination comprising a catch bar, means for raising, lowering, advancing and withdrawing said catch bar, and latch means operative with the catch bar in the withdrawn position to maintain the same in the raised position thereof and to release said catch bar for downward movement as the catch bar approaches its advanced position.

24. In a straight knitting machine, the combination comprising a catch bar, means for raising, lowering, advancing and withdrawing said catch bar, pivotally mounted latch means arranged for engagement with said catch bar, and means for positioning said latch means to support said catch bar as said catch bar is withdrawn and raised to its elevated, rearward position, said catch bar as it advances having movement relative to said latch means to render the latch means inoperative.

25. In a straight knitting machine having a slur cock bar longitudinally reciprocable for advancing the knitting machine sinkers, and a catch bar having horizontal motion for withdrawing the advanced sinkers and also vertical movement for engaging and releasing the sinkers, the improvement which comprises means for horizontally advancing and withdrawing said catch bar, movable means for maintaining said catch bar in elevated position and adapted to release the catch bar for downward movement in the advanced position thereof, cam-like means associated and movable with said slur cock bar, means associated and movable with said catch bar and adapted to engage said cam-like means and effect raising movement of said catch bar during movement of said slur cock bar, and means for moving said movable means into position for maintaining said catch bar in the elevated position thereof when the catch bar is in its rearward and elevated position.

its rearward and elevated position.

26. In a straight knitting machine, the combination comprising vertically movable catch bar means, a reciprocable slur cock bar, a cam roller supported by and movable with said catch bar

means, and cam means carried by said slur cock bar and positioned for engagement with said roller, said cam means presenting a surface extending longitudinally of the slur cock bar and 5 having cam faces adjacent opposite ends thereof, said roller during each stroke of said slur cock bar being adapted to ride up one of said cam faces to elevate said catch bar means, to ride on said surface for maintaining the catch bar means 10 in the elevated position for a predetermined interval, and to ride down the other of said cam faces for lowering said catch bar means.

15 faces for lowering said gates, said faces comprising at least two parts relatively adjustable to vary the spacing between the cam faces adjacent the opposite ends thereof.

28. Apparatus as defined in claim 26, wherein
the roller is supported from the catch bar means
20 by an eccentric stud, and the eccentric stud is
adjustably secured to the catch bar means to
provide adjustment of the roller relative to said
catch bar means.

29. The improvement in straight knitting machines which improvement comprises at least two catch bars adapted to have independent horizontal sinker operating movement, means providing each of said catch bars with independent horizontal movement, and means for providing 30 one of said catch bars with vertical movement, the other of said catch bars normally being so supported from the catch bar having said vertical movement as to partake of the latter.

30. The improvement in straight knitting machines which improvement comprises at least three catch bars, means providing each of said three catch bars with independent horizontal movement, and means for providing two of said catch bars with vertical movement, the other of said three catch bars normally being so supported from at least one of said two catch bars as to partake of the vertical movement thereof while being free for independent horizontal movement.

31. The improvement in a straight knitting machine having cam means and a plurality of knitting sections, each section including a series of needles, a series of sinkers, and a reciprocating yarn carrier, which improvement comprises catch bar means in at least three sections, each catch bar section being adapted to have both horizontal and vertical motion for withdrawing at least one of said series of sinkers relative to the corresponding needles after each yarn sinking operation, the intermediate one of said catch bar sections being normally supported by and transversely slidably relative to the other two of said three catch bar sections whereby each catch bar section has independent horizontal movement in withdrawing sinkers and said intermediate catch bar section is adapted to be raised by and lowered with said other two catch bar sections during the vertical movement thereof, a plurality of means separately controlled by said cam means for individually operating each of said catch bar sections to provide the horizontal motion thereof, and means for individually operating each of said other two catch bar sections to provide the vertical motion thereof.

32. In a straight knitting machine having a main cam shaft and a plurality of knitting sections, each section having a series of sinkers and sinker advancing means, the improvement which comprises a plurality of independently operable catch bar means, each adapted to withdraw the

sinkers of at least one knitting section, and separate operating means between each of said catch bar means and said main cam shaft.

33. In a straight knitting machine, the combination comprising a plurality of knitting sections, each section having a series of sinkers, a plurality of independently operable catch bars, each bar being adapted to operate the sinkers of one or more knitting sections, a cam shaft, and separate driving means interposed between said cam shaft and each of said catch bars, each of said driving means including an oscillatable catch bar shaft.

34. In a straight knitting machine, the combination comprising a plurality of knitting sections, each section having a series of sinkers, a plurality of independently operable catch bars, each bar being adapted to operate the sinkers of one or more knitting sections, a cam shaft, separate driving means interposed between said cam shaft and each of said catch bars to provide independent horizontal motion for each of said catch bars, each of said driving means including an oscillatable catch bar shaft, means for advancing said sinkers in yarn sinking operations, and a separate control means for each of said catch bars to provide the same with vertical movement for releasing and engaging the corresponding sinkers, each of said separate control means being interposed between the corresponding catch bar and said sinker advancing means.

35. In a straight knitting machine having reciprocable sinkers, the combination comprising movable sinker advancing means, movable sinker withdrawing means, means for horizontally operating said sinker withdrawing means between forward and rearward positions, and means adapted to provide for raising and lowering said sinker withdrawing means to release and engage said sinkers, said raising and lowering means being interposed between said sinker advancing means and said sinker withdrawing means, said operating means and said raising and lowering means cooperating to move said sinker withdrawing means from rearward to forward positions after said sinkers are advanced and while said sinker withdrawing means is in raised position, then to lower said sinker withdrawing means into engagement with said sinkers, then to move said sinker withdrawing means to its rearward position while lowered to effect withdrawal of said sinkers, then to raise said sinker withdrawing means to release said sinkers for operation by said advancing means, and then to maintain said sinker withdrawing means in its raised rearward sinker releasing position during the operation in which the sinkers are being moved to their advanced position.

36. In a straight knitting machine having a series of sinkers, the combination comprising reciprocable means adapted in each stroke thereof to advance said sinkers in succession, means movable from forward to rearward position for withdrawing said sinkers en masse from the advanced position thereof and movable vertically to release and engage said sinkers, operating means for horizontally moving said sinker withdrawing means between forward and rearward positions, a cam-like member mounted for movement with said sinker advancing means and having a substantially flat face and two similar sets of stepped cam faces, said cam face sets being arranged at opposite ends of said flat face and being adapted to alternate as the leading cam face set during

reciprocation of said sinker advancing means, and a roller supported by said sinker withdrawing means for engagement with said cam-like member during each stroke of said sinker advancing means, said operating means being adapted to so move said sinker withdrawing means that in one direction of travel of the sinker advancing means said roller engages one cam face of each of said sets, and a different cam face in each set during travel of said sinker advancing means in the reverse direction.

37. A machine as in claim 36 wherein the flat face of the cam-like member supports said roller for maintaining said sinker withdrawing means in raised sinker releasing position during operation of said sinkers by said sinker advancing means, and said sinker withdrawing means are shifted to the forward position thereof while said roller is supported on said flat face and to the rearward position thereof after said cam-like member has released said roller and thereby provided for lowering of said sinker withdrawing means into engagement with the sinkers in the advanced position thereof.

38. A machine as in claim 36 wherein the cam-like member is formed of relatively adjustable parts to vary the spacing between said sets of cam faces and an overlapping joint is provided between said parts.

39. A safety device for a straight knitting machine having a plurality of sinkers, a reciprocable, sinker advancing means, a catch bar movable between an elevated sinker releasing position and a lowered sinker engaging position and means for shifting said catch bar while in engagement with said sinkers to withdraw the same from their advanced position, said safety device comprising movable means for controlling the lowering movement of said catch bar, and an element adapted to be mounted for reciprocation with the sinker advancing means, said element during part of each stroke thereof being in a position to limit movement of said controlling means to thereby prevent lowering of the catch bar into sinker engaging position.

40. In a straight knitting machine, the combination comprising a plurality of sinkers, a reciprocable slur cock bar for advancing said sinkers, a catch bar movable between an elevated sinker releasing position and a lowered sinker engaging position, an oscillatable catch bar shaft, means operatively connecting said shaft and said catch bar to elevate and lower said catch bar during oscillation of said shaft, means for shifting said catch bar while in engagement with said sinkers to withdraw the same from their advanced position, movable means operatively connected to said shaft for controlling the movement thereof which provides for lowering said catch bar, and a bar-like element secured to said slur cock bar for reciprocation therewith, said element during part of each stroke thereof being in a position to limit movement of said controlling means to thereby prevent lowering of said catch bar into sinker engaging position.

41. In a multi-section straight knitting machine having a main cam shaft, a plurality of independent series of sinkers, and sinker advancing means, the improvement which comprises a plurality of independently operable catch bar means, each adapted to engage and withdraw at least one series of sinkers from the advanced portion thereof, separate operating means between each of said catch bar means and said main cam shaft, each of said operating means being adapted to

impart horizontal advancing and withdrawing movement to the corresponding catch bar means, and means interposed between said sinker advancing means and each of said catch bar means to provide for raising and lowering the same during movement of said sinker advancing means.

42. In a multi-section straight knitting machine having a cam shaft, a plurality of independent series of sinkers, and means for advancing the sinkers of each series in succession, the combination comprising a plurality of disconnected catch bars, each of said catch bars being independently movable both vertically and horizontally, being independently operated, and being adapted to operate at least one and not more than two series of said sinkers; means for independently operating each of said catch bars in a horizontal direction, each of said catch bar operating means including a separate rock shaft, a lever depending from said rock shaft and actuated by said cam shaft to operate said rock shaft, a set of levers arranged in spaced relation and secured to said rock shaft for operation thereby, and a shifter arm operatively connecting each of said last-named levers and the corresponding catch bar for imparting horizontal motion to the latter independent of the horizontal movement of the other catch bars; and separate means for each of said catch bars to provide each catch bar with vertical movement independent of the vertical movement of the other catch bars.

43. In a multi-section straight knitting machine having a cam shaft, a plurality of independent series of sinkers, and a slur cam bar for advancing the sinkers of each series in succession; the combination comprising a plurality of disconnected catch bars, each of said catch bars being independently movable both vertically and horizontally, being independently operated, and being adapted to operate at least one and not more than two series of said sinkers; means for independently operating each of said catch bars in a horizontal direction, each of said catch bar operating means including a separate rock shaft, a lever depending from said rock shaft and actuated by said cam shaft to operate said rock shaft, a set of levers arranged in spaced relation and secured to said rock shaft for operation

thereby, and a shifter arm operatively connecting each of said last-named levers and the corresponding catch bar for imparting horizontal movement to the latter independent of the horizontal movement of the other catch bars; and separate means interposed between each of said catch bars and the slur cam bar to provide each catch bar with vertical movement independent of the vertical movement of the other catch bars.

44. The improvement in straight knitting machines having sinkers and dividers to be advanced and withdrawn during knitting operations, which improvement comprises at least two catch bars arranged substantially in end to end relation and adapted to have independent horizontal movement whereby each catch bar is adapted to advance a series of dividers and then withdraw said series of dividers and also a series of sinkers, means for providing each of said catch bars with said independent horizontal movement, and means for providing one of said catch bars with alternate raising and lowering movements to disengage corresponding withdrawn sinkers and to engage said last-named sinkers in the advanced position thereof, said last-named catch bar providing a rest or support for the other catch bar, whereby said other catch bar is raised by said supporting catch bar, rests on said supporting bar by gravity action to partake of its lowering movements, and is free to move independently of said supporting catch bar in advancing the corresponding dividers and in withdrawing the corresponding dividers and sinkers.

45. In a straight knitting machine having yarn sinking devices, the combination comprising a catch bar for operating said yarn sinking devices, means to provide said catch bar with vertical motion to secure its release from and engagement with said yarn sinking devices, and means to provide said catch bar with horizontal motion for operating said yarn sinking devices, both of said motion providing means being arranged rearwardly of said catch bar.

46. An improvement as recited in claim 35 wherein the movable sinker advancing means is a longitudinally reciprocable slur cam bar.

FRANK G. WEISBECKER.
